C. V. SPRENGNETHEN

HAIR BOBBING GAUGE

Filed April 14, 1924

INVENTOR

CRESCENTIA V. SPRENGERI
by Dr. George Orme Moore.

UNITED STATES PATENT OFFICE.

CRESCENTIA V. SPRENGNETH, OF ST. LOUIS, MISSOURI.

HAIR-BOBBING GAUGE.

Application filed April 14, 1924. Serial No. 706,549.

To all whom it may concern:

Be it known that I, CRESCENTIA V. SPRENGNETH, a citizen of the United States, residing in the city of St. Louis and State of Missouri, have invented a new and useful Hair-Bobbing Gauge, of which the following is a specification.

My invention relates to improvements in hair bobbing gauges and more specifically to gauges for the cutting and trimming of hair from human heads, according to the fashion, now in vogue particularly among young ladies and children, which consists in causing the hair from the top and sides of the head to fall freely from the head and in cutting the hair along a substantially horizontal line in a plane approximating the lower extremities of the ears.

The object of my invention is to provide a device, of simple, inexpensive and durable construction, in the form of an open frame for placement over the head and comprising an element, which surrounds the back and both sides of the head to provide a gauge, or true line, for the guidance of scissors, or hair cutting tools, and, other elements for the establishment and maintenance of the gauge in proper position.

A further object is to provide a hair bobbing gauge comprising elements which may be relatively adjusted whereby the element forming the cutting line may be moved and held in selective positions; and a still further object is to provide a hair bobbing gauge having the recited characteristics and whose various elements may be relatively articulated, or hinged, whereby to provide for its folding into a relatively small compass for storage and transit.

My improvements consist in the novel construction, arrangement and combination of parts as hereinafter fully, clearly and concisely described, definitely pointed out in my claims and illustrated by the accompanying drawing (1 sheet), in which—

Fig. 1 shows a side elevation of my gauge as in use.

Fig. 2 is a plan view of the gauge.

Fig. 3 is a front view of the gauge, and

Fig. 4 is a side view showing the gauge as folded.

My device consists essentially in a gauge element A and suspending means B for the gauge element. By preference the gauge

element A is formed out of a single piece 55 of wire, of substantially semi-circular shape, of a sufficient length to embrace the sides and back of the head and having its free ends anteriorly disposed. Also, by preference, the suspending means B is formed as 60 bows, made of wire, for extension over the head to provide a suspending point at the median point at the back of the head and two opposed suspension points at the sides of the heads. 65

In order that the gauge element A may be moved and held in varying altitudinal planes the suspending means are made relatively adjustable, the forward bow being made of two parts 5 and 6, each having at its lower end an eye 7 for the suspension of the gauge element A and each having at its upper end an eye 8 providing a sliding connection between the upper ends of the parts 5 and 6. Obviously upon a lengthening or 70 shortening of the forward bow as by a relative movement of its parts 5 and 6 the forward ends of the gauge element A will be lowered or raised. For correspondingly bringing the rear part of the gauge element 75 to the plane of its forward ends, as varied by an adjustment of the parts 5 and 6 the rear bow 9 having an eye 10 connected with the gauge element is extended at its upper end between the parts 5 and 6, as shown, and 80 drawn, or moved, forwardly or rearwardly 85 thereof to raise or lower the rear part of the gauge element.

For the locking of the parts 5, 6 and 9 against relative movements in their properly 90 adjusted positions I provide slip rings 11 and 12 and for the more positive securing of the bow 9 against displacement I may provide undulations as at 13.

It is desirable that the device, as a whole, 95 be of minimum weight, for the comfort of the wearer, and yet be of such construction as to preclude distortion, particularly of the gauge element A, hence I employ throughout a relatively small gauged wire and augment the gauge element with a correspondingly shaped piece of wire 14 located in a plane above the gauge and connect it with the gauge as by the links 15, 16 and 17. By preference the links 15 and 16 are formed 100 as integral extensions of the wire 14 and each include an eye 18 for connection with the described eyes 7 of the suspending means 105.

and their lower terminals shaped as at 19 and 20 for the securement of a chin strap, such as 21 for the holding of the device, as a whole, against rearward movement over the head. The link 17 is a separate and distinct piece of wire having at its lower end an eye 22 for connection with the eye 10 of the rear bow and at its upper end a hook 23 for holding the rear bow 9 against lateral movements.

The wire 14, in addition to the structural advantage just recited, serves the very important function of confining the hair within or behind the gauge element A, as 15 obviously with the gauge element forming the cutting line the hair would be unconfin'd except for the wire 14.

In the provision of the readily separable connection between the bows and the hinge 20 connections between the bows and the gauge element I am enabled to fold the whole device, for storage or transit as in Fig. 4.

The folding operation consists in a loosening of the slip rings 11 and 12 to 25 free and separate, or detach, the forward end of the bow 9 from the bows 5 and 6 and in freeing the bow 9 from the hook 23; in swinging the bow 9, on eyes 10 and 22, laterally, and in swinging bows 5 and 6, on 30 eyes 7 and 18, rearwardly, as shown in Fig. 4.

I claim:

1. A hair bobbing gauge comprising a pair of similarly shaped elements, means for fixedly securing said elements in vertically spaced relationship whereby the one may serve to guide a hair cutting tool and the other serve to confine the hair immediately above the tool guiding element and a frame, comprising relatively adjustable members, 40 whereby the recited elements may be held in selective positions upon a user's head.

2. A hair bobbing gauge, comprising a pair of vertically spaced, parallel, and similarly shaped elements, the lowermost one of 45 which serves as a guide for a cutting tool and the uppermost one of which serves as a hair confining means, means for holding said elements upon a user's head, comprising a bow consisting of relatively adjustable 50 parts for the support of the forward end of said elements and a bow for the support of the rear end of said elements having its forward end extended between the parts of the first mentioned bow, means for relatively detachably securing the parts of the forward bow and the forward end of the rear bow, and means for hingedly connecting all of the bows to said hair confining and tool guiding elements.

CRESCENTIA V. SPRENGNETH.
